UNITED STATES PATENT OFFICE

WILLIAM C. TREGONING, OF WAUWATOSA, WISCONSIN, ASSIGNOR TO CUTLER-HAMMER, INC., OF MILWAUKEE, WISCONSIN, A CORPORATION OF DELAWARE

COMBINED PLUG RECEPTACLE AND WARNING LIGHT FIXTURE

Application filed November 6, 1929. Serial No. 405,164.

This invention relates to improvements in combined plug receptacle and warning light fixtures.

An object of the invention is to simplify the construction and facilitate assembly of the parts of devices of the aforementioned character.

Another object is to provide a combined device of the aforementioned character the parts of which are so compactly arranged that the device as a whole may be mounted in an outlet box of the size ordinarily intended for reception of a single plug receptacle, thus effecting an economy in the amount of material required and rendering the device very neat and attractive in appearance.

Another object is to provide novel means for supporting the jewel or bull's-eye with respect to the face plate of the device.

Another object is to provide a novel form and arrangement of the lamp and plug receiving contacts of the device.

Other objects and advantages of the invention will hereinafter appear.

The accompanying drawing illustrates an embodiment of the invention which will now be described, it being understood that the device illustrated is susceptible of modification in certain details thereof without departing from the scope of the appended claims.

In the drawing, Figure 1 is a top plan view of a combined plug receptacle and warning light fixture constructed in accordance with my invention.

Fig. 2 is a vertical sectional view on the line 2-2 of Fig. 1, the lamp bulb and the face plate and jewel being shown in position.

Fig. 3 is a perspective view, in separated relation, of the several parts of the device illustrated in Fig. 2.

Fig. 4 is a top plan view of one of the punched metal parts of the device, and

Fig. 5 is a bottom plan view of the one-piece molded insulating base.

Referring to the drawing, the numeral 10 designates in general the molded insulating base of the device. Said base is preferably of substantially rectangular contour, and as best shown in Fig. 5 the lower surface thereof is recessed to a predetermined depth and

in conformity with the vertical sides of the base, as indicated at 11, thus leaving a relatively thin wall 12 around said recess. The four corners of the base are in the form of vertical substantially cylindrical enlargements 13, 14, 15 and 16 each enlargement being provided with a through passage or perforation to accommodate a suitable securing element, as hereinafter described.

Extending upwardly from the recess 11 at one end thereof is a substantially cylindrical recess 17 which terminates in a shoulder 18 which is perforated as indicated at 19 in register with the downwardly tapered recess or passage 20 in the upper face 21 of the base. Extending radially from the recess 17 in a plane intermediate the depth of the latter is a substantially rectangular recess 22, said recess 22 and its branch 23 being located in a common plane.

Adapted to seat within recess 22 is a punched sheet metal member 24, said member having an integral arm 25 which is likewise adapted to seat within the branch 23 of said recess. The integral ring-shaped end 26 of member 24 is offset upwardly therefrom, as indicated at 27. The inner edge of said ring is provided with a substantially rectangular notch 28, and the area 29 radial to said notch is bent as shown to offset the adjacent ends of the inner edge 30 of said ring.

As best shown in Fig. 2 the ring 26 is positioned within recess 17 at a point adjacent to the shoulder 18 of the latter, and the same is adapted to receive and retain the threaded shell contact 31 of a lamp bulb 32. Integral with and preferably extruded upwardly from the member 24 at the point illustrated is a stud or projection 33, said stud being adapted to penetrate a perforation in the horizontal foot portion of an upwardly extending reflexed resilient contact 34, said stud being riveted over said foot portion (as shown in Fig. 2) to rigidly secure said contact to member 24.

Extending upwardly from recess 22 is a recess 35 of substantially rectangular form in cross section into which said contact 34 is adapted to extend, said recess 35 having a

shoulder 36 adapted to overlie the reflexed portion 37 of said contact, and one wall 38 of said recess being preferably inclined to facilitate insertion of said contact. As shown the upper portion of recess 35 is located within a substantially elliptical portion 39 of insulating material which is integral with and extends a substantial distance above the upper surface 21 of the base, 10 said portion 39 having an opening 40 to provide access to the contact 34 of one of the blade contacts of a plug cap (not shown).

Also extending upwardly from recess 22 and projecting laterally therebeyond is a 15 recess 41 which is likewise of substantially rectangular form in cross section, and said recess is provided with a shoulder 42 adapted to overlie the reflexed end 43 of a resilient contact member 44 the horizontal foot 20 portion of which is rigidly secured to the upwardly offset end portion 45 of a punched sheet metal member 46 as by means of the upset integral projection 47 on the latter.

Integral with and extending laterally at 25 a right angle from member 46 is an arm or branch 48 which is adapted to seat within a correspondingly shaped branch 49 of recess 22, the horizontal wall of branch recess 49 being offset downwardly with respect to 30 the horizontal wall of recess 22. Interposed between the metal members 24 and 46 and insulated therefrom as by means of a pair of relatively thin substantially rectangular insulating plates 50 and 51 is the horizontal 35 portion 52 of a resilient metal strip, said plates being slightly shorter than the recess 22 in base 10 whereby the same may be offset endwise with respect to each other upon assembly of the parts. One end of said strip 40 is bent upwardly and then reflexed downwardly to provide a relatively short auxiliary contact 53 which is adapted to underlie the shoulder 54 formed in recess 41 and to 45 also underlie the aforementioned reflexed contact 43.

The other end of said interposed metal strip is inclined downwardly and then upwardly, as best illustrated at 55 and 56, respectively, in Fig. 3, the end 56 being adapted to yield upon engagement thereof by the center contact 57 of a lamp (Fig. 2). The extension 39 of the base is provided with a slot or passage 58 in register with the recess 41 to provide for access to the contacts 43 and 53 by the other blade of a plug cap. One wall 59 of recess 41 is inclined outwardly as shown to facilitate insertion of said contact 43.

Located in correspondingly shaped shallow recesses at opposite sides of the upper face 21 of the base are a pair of terminal plates 60 and 61, said plates being tapped to accommodate the usual binding screws 60^a and 61^a and having the usual wire-retaining 65 lugs 60^b and 61^b, the face 21 of said base

being recessed to provide clearance for the shanks of screws 60^a and 61^a. Plates 60 and 61 are provided with tapped openings as shown for cooperation with the shanks of securing screws 62 and 63, which respectively penetrate the perforations in arms 25 and 48 of members 24 and 46 and registering passages in the base 10 to provide for clamping said members to the base and to provide the proper electrical relation therebetween.

Underlying the base 10 and substantially conforming to the shape thereof is a relatively thin plate 64 of fiber or other suitable tough or slightly flexible insulating material, said plate having perforations adapted to register with the passages in the aforementioned corners 13, 14, 15 and 16 of base 10. Screws 65, 66, 67 and 68 are respectively adapted to penetrate said perforations and passages and to take into pairs of tapped 80 openings in the supporting lugs 69 and 70, which may be of any desired shape, said lugs as shown being provided with one form of plaster or wall engaging portions 69^a and 70^a. The base 10, bottom plate 64 and lugs 69 and 70 are thus rigidly secured to each other, and the device may therefore be attached in the usual manner to an outlet box or similar support.

The extension 39 of the base is provided with relatively small ledges 71 and 72 at opposite sides thereof, the ledge 71 being best illustrated in Fig. 3, said ledges being adapted for engagement by the lower surface of the metal flush or wall plate 73, which is perforated as shown at 74 in Fig. 3 to accommodate the upper end of extension 39. Plate 73 is also provided with a perforation 75 which registers with the lamp receiving portion of the base, said plate having a pair of integral lugs 76 and 77 which are initially bent downwardly at right angles to the plate to permit free upward insertion of the substantially dome-shaped transparent jewel 78 through the perforation 75.

Jewel 78 preferably consists of molded glass of the desired color and formed integrally with the lower edge thereof are pairs of spaced substantially radial projections or feet 79 and 80 the upper surfaces of which engage the lower surface of plate 73 and between each pair of which the lugs 77 and 76 are respectively bent into engagement with the lower edge of the jewel to permanently secure the latter to said plate.

Projecting above the surface 21 of the base are a pair of ledges 81 and 82 upon which the projections or feet 79 and 80 of the jewel are adapted to rest, whereby horizontal alignment of base 10 with respect to wall plate 73 is insured upon securement of the latter to former. The means for securing the wall plate 73 to the base preferably comprises a pair of screws 83 and 84 which are adapted to penetrate diagonally located countersunk

perforations in plate 73 and take into tapped openings in integral offset portions 85 and 86 of lugs 69 and 70, respectively.

The upper surface of extension 39 may be 5 paneled as shown or otherwise decorated to improve the appearance thereof, and also if desired the access openings 40 and 58 in said extension may be made of different dimensions as shown or otherwise arranged for 10 operation with either a standard or a polarized type of plug with parallel contact blades.

What I claim as new and desire to secure by Letters Patent is:

1. In a combined plug receptacle and warning light fixture, in combination, a one-piece molded insulating base having a plurality of recesses extending upwardly from the lower surface thereof, center and screw shell lamp contacts located in one of said recesses, 15 attachment plug receptacle contacts in other of said recesses, wiring terminal plates located in spaced relation to each other on the upper surface of said base, a pair of screws penetrating said base and having mechanical 20 and electrical connection with the respective terminal plates and with certain of said contacts, said screws clamping all of said contacts in position within said base, and means 25 comprising a plurality of plates for normally insulating certain of said contacts from other of the same and from one or both of said terminal plates.

2. In a combined plug receptacle and warning light fixture, in combination, a one-piece 30 molded insulating base of substantially rectangular contour, said base having a substantially cylindrical recess adjacent to one end thereof and a pair of substantially parallel recesses adjacent to the other end thereof, 35 said recesses extending upwardly from the bottom surface of said base, constricted passages affording access to each of said recesses from the upper surface of said base, attachment plug receiving contacts within the 40 respective parallel recesses, center and screw shell lamp contacts in said cylindrical recess, means for permanently electrically connecting said screw shell contact and one of said plug receiving contacts, means comprising an 45 auxiliary plug receiving contact integral with said center lamp contact, said auxiliary contact being located in inwardly spaced relation to the other of said first mentioned plug receiving contacts, a pair of wiring terminal 50 plates on the upper face of said plate, and a pair of screws penetrating said base and engaging the respective terminal plates, said screws being arranged to clamp all of said contacts to said base.

3. In a combined plug receptacle and warning light fixture in combination, a one-piece molded insulating base of substantially rectangular contour, said base having a substantially cylindrical recess adjacent to one end 55 thereof and a pair of substantially parallel

recesses adjacent to the other end thereof, said recesses extending upwardly from the bottom surface of said base, constricted passages affording access to each of said recesses from the upper surface of said base, attachment plug receiving contacts within the 70 respective parallel recesses, center and screw shell lamp contacts in said cylindrical recess, means for permanently electrically connecting said screw shell contact and one of said plug receiving contacts, means comprising an auxiliary plug receiving contact integral with 75 said center lamp contact, said auxiliary contact being located in inwardly spaced relation to the other of said first mentioned plug receiving contacts, a pair of wiring terminal plates on the upper face of said plate, a pair of screws penetrating said base and engaging the respective terminal plates, said screws being arranged to clamp all of said contacts to 80 said base, supporting lugs on the upper face of said base, a relatively thin insulating cover plate on the lower face of said base, and means comprising screws penetrating said cover plate, base and lugs for clamping the 85 same in assembled relation to each other.

4. In a combined plug receptacle and warning light, in combination, a one-piece molded insulating base having recesses and passages in the upper and lower faces thereof and 90 adapted to be formed by a straight line molding operation, plug receiving contacts insertable from the lower face of said base and located in certain of said recesses, sheet metal members rigidly secured to the respective contacts, said sheet metal members having portions seated within said base in spaced parallel planes, a screw shell lamp receiving contact integral with one of said sheet metal members and located within another of said recesses, a strip of metal having portions thereof offset to form a center lamp contact at one end and an auxiliary plug receiving contact at the other end, the intermediate portion of 95 said strip being located between said sheet metal members but insulated therefrom, wiring terminal plates located on opposite sides of the upper face of said base, and means for mechanically and electrically connecting said sheet metal members and the respective 100 terminal plates whereby all of said parts are rigidly secured to said insulating base.

5. In a device of the character described, the combination with a one-piece molded insulating base having a plurality of recesses in the lower face thereof, one of said recesses being substantially circular in cross section and another of said recesses being substantially rectangular in cross section, said base having passageways extending from the upper face thereof and communicating with the respective recesses, a punched sheet metal member having a ring-shaped portion at one end thereof, said ring-shaped portion having 110 a substantially rectangular notch in the inner 115

- edge thereof, the portions of said ring adjacent to said notch being offset for cooperation with the threaded contact of an electric lamp, a reflexed resilient contact and means integral with said punched metal member for rigidly securing said contact thereto in spaced relation to said ring-shaped portion, a perforated arm integral with said metal member and extending outwardly at right angles to
- 5 the main body thereof, a wiring terminal plate on the upper face of said base, and means penetrating said arm and said base and engaging said terminal plate to rigidly secure said punched metal member to said base.
- 10 6. In a device of the character described, the combination with a one-piece molded insulating base having a plurality of recesses in the lower face thereof, a contact located in
- 20 one of said recesses, said contact being formed to receive and support the threaded base of a lamp, reflexed resilient contacts located in other of said recesses, said reflexed contacts being adapted for engagement by the blades
- 25 of a plug cap, a resilient metallic strip formed at one end to provide an auxiliary reflexed contact, said auxiliary contact being located in one of said last mentioned recesses in inwardly spaced relation to another of
- 30 said reflexed contacts, the other end of said metallic strip being downwardly offset from the main body thereof and adapted for cooperation with the center contact of a lamp, a pair of wiring terminal plates located in
- 35 recesses on the upper face of the base, and means comprising a pair of screws penetrating said base and the respective terminal plates and engaging certain of said contact elements to clamp all of the latter in assembled relation to said base.
- 40 7. As an article of manufacture, a punched sheet metal member having a flat body portion and a ring-shaped end integral therewith but offset upwardly therefrom, said
- 45 ring-shaped portion having a substantially rectangular notch in the inner edge thereof, the portions of said ring adjacent to said notch being offset relatively to each other, said member having a stud extending from
- 50 the body portion thereof, and a reflexed resilient contact having a perforated foot portion to cooperate with said stud and over which the latter is upset to secure said contact to said member, said body portion being
- 55 perforated at a point between said reflexed contact and said ring-shaped end to provide for attachment of said member to a suitable support.

60 In witness whereof, I have hereunto subscribed my name.

WILLIAM C. TREGONING.
